UNITED STATES PATENT OFFICE.

GEORGE H. GARCELON, OF SWISSVALE, PENNSYLVANIA, ASSIGNOR TO WESTINGHOUSE ELECTRIC & MANUFACTURING COMPANY, A CORPORATION OF PENNSYLVANIA.

CONNECTOR.

1,379,681.

Specification of Letters Patent. Patented May 31, 1921.

Application filed February 3, 1917. Serial No. 146,475.

To all whom it may concern:

Be it known that I, GEORGE H. GARCELON, a citizen of the United States, and a resident of Swissvale, in the county of Allegheny and

5 State of Pennsylvania, have invented a new and useful Improvement in Connectors, of which the following is a specification.

10 My invention relates to connectors and particularly to connectors or terminal members of the solderless type.

One object of my invention is to provide a connector that shall have means for so intimately connecting conductors that the necessity of soldering the connection is precluded.

15 Another object of my invention is to provide a connector of the above indicated character that shall be simple and effective in operation and economical to manufacture.

20 In practising my invention, I provide an internal screw-threaded member having an opening at the ends and a slot or opening extending along one side thereof near one of its ends. The conductors that are to be se-
25 cured together are inserted in one end and adapted to extend through the slot in the side. A screw-threaded member is adapted to be received in the other end of the internally screw-threaded member for the pur-
30 pose of clamping the conductors into intimate engagement.

In the accompanying drawings, Figure 1 is a view, partially in section and partially in elevation, of a connector embodying my 35 invention and Fig. 2 is an end view, partially in section and partially in elevation, of the connector shown in Fig. 1.

The connector 1 comprises an internally 40 screw-threaded cylindrical member 2 having openings 3 and 4 in its respective ends and a longitudinal opening or slot 5 at one side thereof adjacent to the end 4. The slot 5 is longer at its outer edge than at its inner edge to provide a sloping shoulder 10, at its 45 inner end, having a relatively sharp edge portion 11 against which ends 8 of conductors 6 and 7, that are adapted to be received in the end 3 of the member 2, are so bent as to extend through the slot 5. The ends 8 are 50 bent away from the approach or clamping end of a screw-threaded member 9 disposed in the opening 4 of the member 2 to effect a sharp-biting engagement between the conductors and the connector.

55 The arrangement provides a simple and

effective device that so intimately clamps the conductors together as to eliminate the use of solder.

While I have shown only one form of my invention, it will be understood that it may be used equally well as a terminal member and that various modifications may be made therein without departing from the spirit and scope of the invention as set forth in the appended claims.

I claim as my invention:

1. A connector comprising a member having a longitudinal opening for the reception through one end of a plurality of flexible conductors and a longitudinal side slot extending from the other end thereof to a position intermediate the ends of said opening, said member being interiorly threaded in said opening from the slotted end thereof to a position adjacent the inner end of the slot and having a sharp-edged sloping shoulder constituting the inner end of the slot and engaging said conductors, and a screw-threaded member co-operating with the threads of said first member to jam said conductors together against the sharp edge of said shoulder.

2. A connector comprising a member having a longitudinal opening for the reception through one end of a flexible conductor and a longitudinal side slot extending from the other end thereof to a position intermediate the ends of said opening, said member being interiorly threaded in said opening from the slotted end thereof to a position adjacent to the inner end of the slot and having a sloping shoulder constituting the inner end of the slot and engaging said conductor, said slot being longer at its outer edge than at its inner edge, and a screw-threaded member co-operating with the threads of said first member to jam said conductor against said sloping shoulder.

3. A connector comprising an interiorly threaded member having a slot extending from one end to an intermediate portion thereof and a sloping shoulder constituting the inner end of the slot, said slot being longer at its outer edge than at its inner edge, and a second threaded member extending into said first threaded member from the slotted end of the latter to clamp a conductor against said sloping shoulder.

4. A connector comprising a hollow member having a slot extending from one end to

an intermediate portion thereof and a sloping shoulder constituting the inner end of the slot, said slot being longer at its outer edge than at its inner edge, and a member 5 movable in a hollow member to clamp a conductor against said sloping shoulder.

5. A connector comprising a hollow member having a slot in a wall thereof and a sloping shoulder constituting one end of the

slot, said slot being longer at its outer edge 10 than at its inner edge, and a member movable in the hollow member to clamp a conductor against said sloping shoulder.

In testimony whereof I have hereunto subscribed my name this 30th day of January, 15 1917.

GEORGE H. GARCELON
